UNITED STATES PATENT OFFICE.

FREDERICK A. SWAN, OF CLIFTONDALE, MASSACHUSETTS.

TERMINAL FOR ELECTRIC FITTINGS.

No. 897,674.

Specification of Letters Patent.

Patented Sept. 1, 1908.

Application filed April 26, 1907. Serial No. 370,352.

To all whom it may concern:

Be it known that I, FREDERICK A. SWAN, a citizen of the United States, residing in Cliftondale, in the county of Essex and State of Massachusetts, have invented an Improvement in Terminals for Electric Fittings, of which the following description, in connection with the accompanying drawing, is a specification, like letters on the drawing representing like parts.

In most electrical fittings, such for instance as rosettes, lamp-sockets, outlet boxes, etc., the conducting wires are connected to terminals or terminal plates by being passed under the heads of binding screws or nuts. While this manner of connecting the wires to the terminals answers so far as making a good electrical connection is concerned, yet if the conducting wires are so located that they are subjected to any strain, they are apt to be pulled from under or away from the binding screws or nuts, thus breaking the electrical connection.

It is the object of my present invention to provide a novel form of terminal for electrical fittings to which the conducting wire may be connected in such way that it will be impossible for the wire to be pulled from under the binding screw or nut by any strain on the wire.

My improved terminal is especially adapted for use in rosettes and lamp sockets, and in order to illustrate my invention I have shown it as embodied in electrical fittings of this character. I wish it understood, however, that the terminal is adapted for use generally in electrical fittings of all kinds.

In the drawings, Figure 1 shows a rosette and lamp socket, each having my invention applied thereto, the rosette being shown in section and the lamp-socket being broken out to show the invention; Fig. 2 is an under side view of the base of the rosette.

3 is the base of any ordinary rosette, and 4 is the cap thereof. This rosette has the usual terminal plates 5 to which the conducting wires 6 are connected and in the embodiment of the invention herein shown said wires lead to the terminals 7 of the lamp-socket 8 which terminals are of some suitable conducting material. The terminals herein shown have the usual binding screws 9 under which the ends of the conducting wires 6 are clamped, as usual. In order to relieve the binding screws and the portion of the conducting wire 6 clamped thereunder from any

strain to which the said conducting wires may be subjected, I form each of the terminals with a head 10 around which the conducting wire 6 may be wrapped, as plainly seen in the drawings. I find one convenient way of making these terminals is to provide each terminal with the neck 11 connecting the body thereof with the head 10 and preferably the head 10 is formed on each side with the recesses 12 and on its end with another recess 13.

In connecting a conducting wire to my improved terminal the end of the wire is first clamped under the binding screw 9 and then said wire may be wrapped around the head, as shown in the drawings, said wire being received in the recesses 12 and 13. With the wire thus attached to the terminal, any strain on the wire will come directly on the head 10, but will not be transmitted to the portion of the wire which is clamped under the binding screw 9, and therefore said head will relieve the binding screw from any strain to which the conducting wire is subjected. In this way all danger of the circuit being broken by the wire becoming pulled from under the binding screw is avoided. A terminal of this construction can be used not only in rosettes and lamp-sockets, but in any electrical fitting having terminals to which conducting wires are secured. Where the terminal of this shape is used in connection with a rosette, I will preferably provide the base of the rosette with the central recess 14 in which the heads 10 are received, said recess affording plenty of space to wrap the wire around the head. Where the terminal is used in a lamp-socket, the head thereof may be received in the recess 15 formed in the porcelain body 16.

In practice I prefer to strip the insulation from the portion of the conducting wire which is wrapped about the head 10, for by doing so the electrical connection between the wire and the terminal is increased by the wrapping of the wire around the head. The form of terminal herein shown, therefore, not only serves to relieve the binding screw from any strain to which the wire may be subjected, but also permits a better electrical connection to be made.

It is not essential to my invention that the portion of the terminal about which the conducting wire is wound or wrapped should be of the shape shown herein, for I believe I am the first to provide a terminal for an elec-

trical fitting with a device to relieve the binding screw from any strain to which the conducting wire may be subjected, and I wish to claim this feature broadly. I have found, however, that the form of terminal herein shown gives good results and is convenient to use.

Having described my invention, what I claim as new, and desire to secure by Letters 10 Patent is:

1. In an electrical fitting, the combination with a terminal of conducting material, of means to detachably connect a conducting wire thereto, said terminal having integral therewith means to relieve said connecting means from any strain to which the wire may be subjected.

2. In an electrical fitting, the combination with a terminal, of a conducting wire, and means to detachably connect said wire to the terminal, said terminal having as an integral part thereof a portion about which the con-

ducting wire may be wrapped thereby to provide sufficient frictional engagement between the wire and said portion to withstand the 25 strain to which the wire may be subjected.

3. The combination with a fixed electrical fitting having a terminal, of a conducting wire connected thereto and suspended therefrom, a second fitting also having a terminal and means to connect the conducting wire to said terminal, whereby said second fitting is suspended from the fixed fitting, each terminal of each fitting having as an integral part thereof means to relieve the connection 30 between it and said wire from any strain.

In testimony whereof, I have signed my name to this specification, in the presence of two subscribing witnesses.

FREDERICK A. SWAN.
